DESIGN FOR A DISPLAY DEVICE OR SIMILAR ARTICLE

Charles Walter Watkins, Kingston, Pa.

Application July 9, 1943, Serial No. 110,637

Term of patent 14 years

To all whom it may concern:

Be it known that I, Charles Walter Watkins, a citizen of the United States, residing at Kingston, in the county of Luzerne and the State of Pennsylvania, have invented a new, original, and ornamental Design for a Display Device or Similar Article, of which the following is a specification, reference being made to the accompanying drawing, forming part thereof.

Figure 1 is a view in front elevation of a display device or similar article embodying my new design; and

Figure 2 is a view in side elevation.

I claim:

The ornamental design for a display device or similar article, as shown.

CHARLES WALTER WATKINS.
